Application October 29, 1945, Serial No. 625,364

2 Claims. (Cl. 177—380)

1

This invention relates generally to improvements in telemetric systems of the type disclosed in the previously filed application of Gabriel M. Giannini, Ser. No. 597,459, filed June 4, 1945. In that application, a system is described which consists essentially of a transmitter which generates a series of spaced electrical pulses of a sign dependent upon the direction of actuation of the transmitter. The generated pulses actuate a receiver instrument to drive it step by step in either one direction or the opposite, dependent upon the sign of the impulse or impulses received. The system is in essence a step by step system, in which the receiver is actuated in consonance with the initial actuation of the transmitter, so that the receiver may act as a remote indicator or as a remote actuating motor in a system of remote control.

In the system as described in the prior application, both the transmitter and the receiver instrument involve magnetic circuits including a movable magnet. In the transmitter instrument the movable generating magnet is actuated by a magnetic ratchet mechanism which has the function of moving the generating magnet slowly in a direction which depends upon the direction of initial actuation of the transmitter, and then of releasing the moving generating magnet to be quickly snapped back to its initial position by magnetic forces. The rapid change in magnetic flux during the rapid back movement of the generating magnet, generates an electric pulse of short duration in a generating coil associated with the magnetic circuit.

In the receiver instrument of the Giannini application a moving magnetized armature is utilized, that armature being moved selectively in opposite directions from a normal central position by opposite polarizations of an electro-magnetic circuit which is energized by the received pulses.

Certain practical difficulties have been found in the described system. Without going into detail, it has been found that the efficiency of the system is relatively low, due to the relatively large inertia of the moving parts and to the relatively large amount of energy which must be applied to the transmitter in order to provide a given amount of finally delivered energy at the receiver. It has also been found that considerable energy is involved in the movement of the moving generating magnet to its neutral position, and that the forces involved in operation are quite variable and non-linear.

It is the general object of the present invention

2

to overcome the difficulties and shortcomings of the previous system, and, in general, to provide an improved transmitter for use in telemetric systems, which gives such a system greatly increased operational efficiency and operational characteristics which are more flexibly controllable by design selections. In telemetering systems the matter of high efficiency and also the size and mass of the component parts are of extreme importance, particularly in situations where space is limited or where the power available for initial actuation is small.

The present invention accomplishes its purposes and objectives primarily by utilizing a movable coil in a magnetic circuit as the pulse generating means. Movable coils, being of neutral polarity when at rest, have no tendency in themselves to assume any particular orientation in the magnetic fields, and are therefore easily moved in those fields to set them for their fast pulse generating movement or to return them to central neutral positions. Their inertia is small, so that the energy involved in accelerating them to high velocities is relatively small. Thus, as will be shown, a typical moving coil system can be made to attain over-all efficiencies several times as great as the system utilizing moving magnets; and size for size or weight for weight the moving coil system delivers several times as much energy at the receiver.

In a typical illustration of the present invention, the transmitter instrument may involve a rotatable coil of the D'Arsonval type in a permanent magnet circuit and a stationary core within the coil. Upon angular displacement of the coil in either direction from its centralized neutral position in the magnetic circuit, and upon release of the coil from the displaced mechanism, a spring element acts to drive the coil back to its normal central position at relatively high velocity, resulting in generation of a pulse of high amplitude and short duration. A ratchet mechanism of suitable type is utilized to initially displace the coil in either one direction or the other depending upon the direction of initial actuation.

A telemetering system, in which the new transmitter is used preferably includes a receiver, in which a similar movable coil and magnetic circuit are utilized, the coil driving a two-way ratchet mechanism which drives a driven member step by step in a direction dependent upon the direction of coil displacement. Any suitable two-way ratchet mechanism may be utilized; for instance, such a mechanism as is shown in the previous application referred to, or such a one as is shown

by way of illustration in this present application. We make herein no claim to the ratchet mechanism in and of itself. The particular mechanism herein shown by way of illustration is the subject-matter of a copending application, Ser. No. 625,257, filed October 29, 1945, by Walter B. Claus.

In the following detailed description we set out preferred and illustrative forms of the new transmitter, referring for that purpose to the accompanying drawings in which—

Fig. 1 is a central longitudinal section showing a typical form of the new transmitter instrument;

Figs. 2, 3 and 4 are sections taken as indicated by lines 2—2, 3—3 and 4—4 on Fig. 1;

Fig. 3a is a fragmentary illustration of parts shown in Fig. 3, with the parts in another position;

Fig. 5 is a diagrammatic perspective illustrating the essentials of a typical form of receiver instrument, and

Fig. 6 is a diagram illustrating the circuiting of the system.

Figs. 1 to 4 are on a scale twice the size of the actual instrument for which some typical figures are given hereinafter.

In the illustrative form of transmitter instrument shown in Figs. 1 to 4 a toroidal coil 10 of rectangular formation is carried at one end by a shaft 11 and at the other end by a short stub shaft 12. These two shafts are journaled in bearings in bracket members 13 which form a part of the framing of the instrument. The coil is preferably formed of enameled wire set in a plastic cement or other composition to make it rigid without the necessity of using a separate frame. Connections to the coil may be made in any usual manner, spiral connector members being shown at 14. The outer end of one of these spiral connectors may be directly grounded to the frame, as is shown for the lower connector in Fig. 1. The other connector 14 may be connected with an insulated terminal, such as that shown at 15. Another grounded terminal is shown at 15a.

Coil 10 rotates in the air gap between two pole pieces 20 and an internal stationary core 21 which is mounted on the two bracket members 13 as shown in Figs. 1 and 2. The two bracket members 13 are mounted upon a main framing member 22. Pole pieces 20 form parts of a permanent magnetic circuit which is made up of the pole pieces, two permanent magnets 25 and a yoke 26. The physical arrangement of the parts of the magnetic circuit with relation to the other parts of the mechanism may be as desired; the arrangement shown in the drawings is merely illustrative.

Coil 10 normally occupies a central neutral position such as shown in Fig. 2 and is yieldingly held in that position by a pair of springs 30 which are mounted at one end in a block 13a, and whose free ends are adapted to press oppositely upon a flat block 31 set on coil shaft 11. In the normal or neutral position block 31 lies flatly between the two springs 30, and when the shaft and coil are displaced in either direction, the springs tend to force them back to the normal position. The action of such a spring system on a flat block tends to be self-damping, so that the oscillations of the shaft and coil, after being forced back to normal position at high velocity, are small. Those oscillations are further minimized by a stop block 13b interposed between the ends of springs 30 and of such width that the

springs close down on that block just before block 31 reaches its central position. That is, when at rest in central neutral position (Fig. 3) the swinging block 31 is decoupled from the springs, and the two springs are decoupled from each other. Thus, as the system reaches the neutral position of Fig. 3 direct impact occurs between the springs and block 13b, dissipating a considerable portion of the energy in the spring and decoupling the spring momentum from the swinging block 31.

The forces exerted by springs 30, and therefore the torque exerted on the coil shaft, may be at least roughly determined by size and design of the springs and by the dimensions of block 31. A suitable means may be provided for further adjusting the spring pressures, as for instance the adjustment screws which are shown at 33.

The means for displacing the coil from its normal neutral position is here shown as embodying a pawl 35 set on the lower end of coil shaft 11, and a star wheel 36 mounted on a shaft 37. In the normal neutral position the outer pointed end of pawl 35 lies on a radial line between shaft 37 and shaft 11, and in a position to be engaged by teeth 38 of the star wheel when that wheel is rotated in either direction. In the particular design here shown the parts are so dimensioned and related that pawl 35 and the coil 10 are swung through an angle of about 34° to one side of the neutral position when a tooth passes under the pawl. Figs. 3 and 3a illustrate for instance the action when star wheel 36 is rotated counter-clockwise as seen in those figures. Fig. 3a shows approximately the position of maximum coil displacement, with a tooth 38 wiping under the end of the pawl. Upon further movement of the tooth counter-clockwise the pawl is released and springs 30 immediately force the pawl and coil back to the neutral position of Fig. 3. Star wheel teeth 38 are spaced far enough apart that the next oncoming tooth is not immediately contacted by the pawl when it reaches its neutral position. It will be understood that in the normal operation of the transmitter mechanism star wheel 36 is rotated relatively slowly, so that the velocity of coil movement during the initial displacement is relatively low as compared with the high velocity of return movement of the coil under the action of springs 30. The latter movement, in the present specific and illustrative design, is designed to occur in about $\frac{1}{100}$ of a second.

Upon slow displacement from normal position to the position of Fig. 3a the current generated in the coil is negligible. Upon rapid return to the normal position, a pulse of high amplitude and short duration is generated, with the current flowing in a determined direction. Continued counter-clockwise rotation of star wheel 36 at relatively low speed will cause the generation of a series of spaced impulses each of high amplitude and short duration and all of the same sign. Rotation of the star wheel clockwise will cause similar pulse generations of the opposite sign, as will be clear without detailed description.

Star wheel 36 or its shaft 37 may be driven directly, either manually or from any mechanism or device. Or, in some installations it may be driven through a gear train such as is illustrated in the drawings. As there shown a shaft 40 is the initially driven shaft of the instrument and gears 41 interconnect shaft 40 with star wheel shaft 37. Where a gearing train or any other driving train with loose play is used between the

initial driver and the star wheel shaft, a spring may be applied to the star wheel shaft to keep the driving train tight at all times and to eliminate the looseness which would otherwise occur by backlash. Such a spring is shown at 45 in the form of a spiral spring having its inner end attached to shaft 31. Spring 45 acts upon shaft 31 in such a direction as to keep tight all of the motion transmission parts between the star wheel and the device or mechanism which initially 10 drives the instrument; if those transmission parts are wholly composed of gearing, spring 45 may act upon the star wheel shaft tending to drive it in either direction, so that backlash is taken up in the selected direction. And to keep the backlash closed, spring 45 is designed to exert a sufficient torque on shaft 31 to overcome frictional losses in the driving train and also to supply the energy which is necessary to displace pawl 35 against the action of springs 30, when the star wheel is rotating in the direction in which spring 45 tends to drive it.

A typical receiver suitable for use with the new transmitter is shown merely diagrammatically in Fig. 5. As there shown the moving coil 111 is mounted on a shaft 110 to rotate in the field between two pole pieces 20 of a magnetic circuit which may be and preferably is the same in essentials as shown in Fig. 1 and preferably includes a core such as shown in Fig. 1. In fact, the magnetic circuit, the coil and its mountings, may preferably be duplicates in the transmitter and receiver of the system. The normal or neutral position of the coil in the magnetic field is such as that shown in Fig. 5. Connections to the coil may be made as shown in Fig. 1, being shown merely diagrammatically at 109 in Fig. 5. Fig. 6 illustrates diagrammatically the circuiting of the transmitter-receiver system, showing a two-wire circuit at 100. One side of the circuit can be grounded so that only one wire is used.

As illustrated in Fig. 5 the coil shaft 110 carries a double-ended pawl arm 113 affixed to it, and pawls 114 are pivotally attached to the ends of that arm and project toward a toothed ratchet wheel 120 so that their free ends 114a lie just under two teeth 120a. These two teeth 120a are not diametrically opposite each other but, as shown in Fig. 5 are located on that side of wheel 120 which faces the pawl arm 113. Pawls 114 are guided by a pair of fixed stop pins 115 which limit their inward movement toward each other so that each pawl will clear the tooth which lies in the position indicated at 120b. Springs 116 press pawls 114 against stop pins 115. A pair of centering springs 117 are shown as acting upon a pin 118 which is set in arm 113; the action of these springs 117, taking pin 118 and shaft 110 between them, being much like the action of springs 30 of Fig. 1 on the flat block 31. A detent spring 125 engages the ratchet wheel to hold its teeth normally in the relative position shown in Fig. 5. A pair of stop pins 130 may be used to limit the swinging movements of pawl arm 113.

The various moving parts of the receiver mechanism, particularly the pawl arm 113 and pawls 114 may be constructed very lightly and to have a small inertia. The coil may be and preferably is constructed and mounted in the same manner as that which has been explained in connection with Fig. 1. A specifically illustrative design for the ratchet mechanism and for the whole receiver is shown, for instance, in the copending application of Walter B. Claus before referred to.

When a pulse of a predetermined sign is im-

pressed on coil 111, the coil will swing in a predetermined direction in the magnetic field, swinging arm 113 with it. Assume for instance that the arm swings clockwise in Fig. 5. Left hand pawl 114 moves upwardly into engagement with left hand tooth 120a and moves that tooth upwardly through a predetermined distance which is preferably equal to the spacing between teeth. Simultaneously the right hand pawl 113 moves down ahead of the right hand tooth 120a, and moves out of the way of that tooth so that it can move forwardly to the position previously occupied by the right hand tooth 120b. Upon cessation of the pulse, centering springs 117 return the pawl mechanism and coil to normal central position, the left hand pawl 114 dragging downwardly over the tooth which has taken the position of 120b, and the right hand pawl 113 moving upwardly and clearing the tooth which then stands in the position 120b. When a pulse of the opposite sign is impressed upon the coil, the coil and the pawl arm swing in the opposite direction, resulting in the rotation of ratchet wheel 120 through a distance of one tooth in the opposite direction.

In a transmitter instrument such as shown in Fig. 1, where the coil is about 0.9 in. long and 0.45 in. wide, wound with 180 turns of No. 38 enameled wire set in plastic, the moment of inertia is 30 very low—about 0.2×10^{-6} in. lb. sec². With springs 30 of such strength as to apply 0.01 in. lb. to the coil per radian of its rotation, the period of the system is about 0.028 sec. and the time period for spring actuated return of the coil through 34° is about 0.01 sec. Low inertia minimizes the energy required, and the high speed of actuation maximizes the amplitude of the generated pulse. In the particular instance for which these figures are given, and where the receiver coil and magnetic circuit are duplicates of those of the transmitter, with field intensities of about 4000 gauss, the torque delivered by the receiver is as much as 0.0023 in. lb. for a 34° angle of swing of the transmitter and receiver coils. 45 The torque generated by the transmitter, and that finally delivered by the receiver coil, are relatively high for instruments of the size under consideration. And the maximum initial torque which must be applied to the transmitter is only 0.006 in. lb.; so that the over-all efficiency is about 38%. The high amplitude and short duration of the pulse delivered by the transmitter, and the high action speed of the receiver, also enable the system to operate at relatively high frequency of pulse succession. In the instance given, that frequency can be as high as about 55 20 per second.

We claim:

1. A transmitter for telemetric systems comprising a magnetic circuit including an air gap, a coil mounted for rotary current-generative movement in the air gap, a stationary core within the coil, elastic means normally holding the coil with its plane normal to the magnetic lines 60 in the gap and acting to return the coil to normal position after displacement therefrom in either direction, said means comprising a flat block coupled with the coil for rotation therewith and a pair of flat springs pressing on opposite faces of the block, a driving member indefinitely rotatable in either of two opposite directions, and ratchet means adapted to cause successive displacements of the coil in a direction dependent upon the direction of rotation of the driving 65 member.

2. A transmitter for telemetric systems comprising a magnetic circuit including an air gap, a coil mounted for rotary current-generative movement in the air gap, a stationary core within the coil, elastic means normally holding the coil with its plane normal to the magnetic lines in the gap and acting to return the coil to normal position after displacement therefrom in either direction, said means comprising a flat block coupled with the coil for rotation therewith and a pair of flat springs pressing on opposite faces of the block, a driving member indefinitely rotatable in either of two opposite directions, ratchet means adapted to cause successive displacements of the coil in a direction dependent upon the direction of rotation of the driving member and tending to drive it in one direction with energy at least sufficient to actuate the coil displacement means.
